APPARATUS FOR FORMING TUBING INTO COILS

Harold W. Payne, San Bernardino, Calif., assignor to Vapor Heating Corporation, Chicago, Ill., a corporation of Delaware

Application June 28, 1951, Serial No. 233,968

3 Claims. (Cl. 153—67)

My invention relates to an apparatus for automatically forming tubing into coils, such as, for example, are used in boilers and steam generators of the water tube type.

Heretofore, tubular coils of the water tube type, such as are used in boilers and steam generators, for the most part, have been formed manually. Particularly, is this true in the case of coils which are of special form such as the type in which the major portions of the convolutions are disposed in parallel planes at right angles to the axis of the coil with adjacent convolutions being connected by an offset portion and with all of the offset portions being in alignment. Such coils are relatively costly and since the coils deteriorate in service and require replacement at periodic intervals, it will be apparent that the replacement of such coils is an important factor in operating overhead expense particularly, in the case of railroads which utilize a large number of such coils in boilers and steam generators used for car heating.

Accordingly, it is an object of my invention to provide an apparatus for automatically forming tubing into coils of various types whereby the coils may be accurately and relatively rapidly fabricated at a fraction of the cost of similar coils made according to prior art methods.

A further object of my invention is the provision of an apparatus of the foregoing character which has a high rate of production, which is relatively simple in its construction and which is highly efficient in operation.

Other and further objects and advantages of my invention will become apparent from the following description when considered in connection with the accompanying drawings in which:

Fig. 1 is a perspective view of a coil forming machine according to my invention.

Fig. 2 is a front elevational view on an enlarged scale of the coil winding mechanism of my invention.

Fig. 3 is a side elevational view of the apparatus illustrated in Fig. 1.

Fig. 4 is a cross-sectional view taken substantially on line 4—4 of Fig. 3.

Fig. 5 is a top plan view of the structure illustrated in Fig. 4.

Fig. 6 is a top plan view with the cover plate removed of the die elements for offsetting the tubing and showing the said elements in separated relation.

Fig. 7 is a similar view as Fig. 6 but showing the die elements in closed relation.

Fig. 8 is a vertical cross-sectional view of one form of tubular coil of the type adapted to be formed by the apparatus of my invention.

Fig. 9 is a front elevation view of the coil winding arbor in condition for winding with certain structural elements removed for purposes of clarity.

Fig. 10 is a similar view showing the arbor in collapsed condition preparatory to removal from the wound coil.

Fig. 11 is a perspective view of a detail of construction.

Fig. 12 is an elevational view of a structure for sup-

2

porting and rotating two sections of tubing in end to end relation so as to simplify the operations for welding said sections together.

Fig. 13 is a cross-sectional view looking in the direction of the arrows 13—13 of Fig. 12.

Referring to the drawings and particularly to the coil winding mechanism illustrated in Figs. 1, 2, 3, 9 and 10, the numeral 20 indicates generally a base supported on legs 21 of the type adapted to render the base 20 adjustable vertically. Supported on the base 20 are side frame members 22 and 23. Supported on frame member 23 and braced by member 24 is a member 26 having a slideway longitudinally thereof. Arranged for sliding movement in said slideway is a plate member 27 on which is carried a bearing journal 28, and spaced therefrom a post 29, the head 31 of which is threaded to receive a lead screw 32, the said lead screw being supported at the opposite end by an extension of the bracket member 24. A collar 33 is carried on the lead screw 32 as also a crank wheel 34. It will be apparent that rotation of the crank wheel 34 in clockwise or counterclockwise direction will effect sliding movement of the bearing 28 to the left or to the right respectively as viewed in Fig. 2. Supported on the side frame member 22 is a bearing 36 in which is journaled a stub shaft 37 on one end of which is keyed a gear 38, the said gear being one of a train of reducing gears indicated, generally by the numeral 39, driven by a motor 41. The opposite end of the stub shaft 37 is enlarged and is centrally bored and has keyed thereon for rotation therewith a driving member 42. The said member includes oppositely directed arms 43 from each face of which projects a pin 44. A projection 45 extends laterally from one of the arms 43 and is adapted to engage with and actuate a switch 40 mounted on frame member 22 for a purpose as will be hereinafter described.

Arbor construction

The coil winding arbor, indicated generally by the numeral 50 comprises a shaft 51, the left-hand end 52 thereof being reduced in size and threaded. Abutting the shoulder 53 on shaft 51 is a chamfered disc 54 and adjacent the said disc 54 is a disc 56. Both the discs 54 and 56 are secured on the shaft 51 by a nut 57 which engages with the threads on the reduced end 52. Carried on the opposite end of the shaft 51 is another chamfered disc 58, the said disc being keyed to the shaft 51, but being adapted for axial movement relative thereto. Suitably anchored in the discs 54 and 58 and extending inwardly from each of the faces thereof are a plurality of posts 59, each of the posts being transversely perforated to receive a bolt or pin 61 on which is pivotally supported a pair of links 62. The links 62 on the respective discs 54 and 58 are in opposed radially aligned relation and each set of opposed pairs of links 62 is adapted to support therebetween a coil supporting member 63 hereinafter to be described. In the embodiment illustrated and as seen more clearly in Fig. 3, six such coil spacing and supporting members 63 are provided. Each of said members is substantially T-shaped in transverse cross-section. The head 65 of each of the said members 63 is formed with a series of transverse grooves 64, the said grooves being spaced a desired distance apart. As seen more particularly in Fig. 3, the transverse portions 66 of the members 63 are arcuately formed and coincide with the bottoms of the grooves 64, thus providing an extended arcuate surface on which the coil to be wound may be supported, the said surface having a radius of curvature, the center of which is the axis of shaft 51. The members 63 are pivotally connected to the links 62 by bolts 67 which pass through registering perforations in the said

parts. Projecting outwardly from the left-hand ends of the members 63 as viewed in Figs. 9 and 10 are pins 68 which are received in registering apertures provided in the plate 56. Similarly, the pins 44 are received in registering apertures provided in the plate 56. Thus, it will be apparent that when the parts are in assembled relation, as illustrated in Figs. 2 and 9, a driving connection is effected between the motor 41 and the tube spacing and supporting members 63.

When the winding arbor 50 is supported for operation the reduced end 52 of the shaft 51 is received in the bore of the stub shaft 37 while the opposite end of the shaft 51 is journaled in the bearing 28. Figs. 2 and 9 illustrate the winding arbor in extended condition as for winding. The winding arbor 50, however, is adapted to assume a collapsed condition after completion of the winding of the coil thereon, in order to facilitate removal of the arbor from the wound coil. Upon removal of the winding arbor and the coil from the apparatus, in a manner as will be hereinafter described, the arbor is caused to assume the condition illustrated in Fig. 9, in which the disc member 58 is moved axially of the shaft 51 so as to pivot the link members 62 in a horizontal direction as illustrated in Fig. 10 to effect inward radial movement of the members 63 thereby reducing the effective diameter of the arbor 51 and permitting the wound coil to be easily slipped off of the arbor.

Roller for supporting tubing

Arranged below the arbor 50 is an elongated roller 71 journaled in end bearings 72 each carried on a gear rack 73 suitably supported and cooperating with a pinion 74 for driving the same, the pinion being axially connected to a ratchet wheel 76 cooperating with a pawl to lock the parts in a position of adjustment. It will be apparent that upon the application of a crank or wrench to the squared end shaft 77 of the pinion that vertical adjustment of the roller 71 may be effected. The roller 71 is substantially co-extensive in length with the winding arbor 50.

Offsetting mechanism

The structure hereinabove described is adapted for winding convolutions of coils arranged in parallel planes at right angles to the axis of the coil. In order to form coils of the type illustrated in Fig. 8 in which the major portions of the convolutions are disposed in parallel planes and at right angles to the axis of the coil with only a small portion of each coil being angularly offset to connect adjacent coils, I have provided means presently to be described which means are synchronized in operation with the operation of the winding arbor 50 to locate all of the offset portions in accurate alignment.

According to my invention, I provide a carriage indicated generally by the numeral 78. The said carriage includes a bed or trackway formed of angle members 79 suitably secured together at each end by tie rods 81. The said angle members are supported on telescoping leg members 82 suitably supported on rollers 83 adapted to ride on rail sections 84 forming a trackway. The telescoping leg members 82 provide for vertical adjustment of the members 79. One of the track sections 84 is provided with a series of notches 86 adapted to cooperate with a latching member 87 mounted on one of the leg members 82 so as to effect locking engagement of the carriage 78 with the said track section so as to prevent movement of the carriage longitudinally of the trackway. Suitably supported on rollers adapted to travel in the trackway 79 is an air motor 88 connected through a solenoid operated valve 90 to a source of compressed air not shown. The piston of the air motor 88 is spring biased so as to effect automatic return of the piston to non-operating position. Suitably supported on the forward end of the air motor 88 are upper and lower plate members 89 and 91 respectively which house die elements 92 and 93, presently to be described. The die elements 92 and 93

are formed in plan substantially as illustrated in Figs. 6 and 7, and as will be apparent are substantially identical in form but are however intended to be used in confronting relation as illustrated in Figs. 6 and 7. The die elements 92 and 93 are formed so that confronting side faces are provided with grooves 94 and 95 semi-circular in cross-section and of a size to accommodate a tube 96 to be operated upon. Thus, when the die elements 92 and 93 are in closed relation, as illustrated in Fig. 7, the portion *a*—*b* of the tube 96 within the die elements is encompassed. As will be apparent by reference to Fig. 6, the portions of the die grooves 94 and 95 at the leading ends of the die elements are offset from the portions of the grooves at the trailing end of the dies, the said portions being connected by an intermediate portion angularly disposed relative to the axes of the two offset portions. Each of the die elements 92 and 93 is pierced as at 97. The outer die element 92 is pivotally secured to the plate members 89 and 91 by a handled pin 98 while the cooperating die element 93 is secured to a clevis 99 as by a bolt 105, the clevis being attached to the end of the piston rod 100 of the air motor 88. Suitably supported as on brackets at the leading end of the die elements 92 and 93 is a roller 101, the said roller serving as a support and guide for the tubing entering the die. The upper plate member 89 is provided with a recess or cutout 102 to accommodate the clevis 99 in its movement.

Supported on the upper plate member 89 on opposite sides of the recess 102 are switches 103 and 104 adapted to be engaged by a member 106 carried on the clevis. A third switch 107 is supported on the plate member 89 and is also adapted to be engaged by the member 106 substantially at the end of the stroke of the piston of the air motor 88. The switches 103 and 104 are connected in electrical circuit with the driving motor 41 and, when actuated by the member 106 in the forward movement of the piston of the air motor, effect an opening of the electrical circuit to the driving motor 41 and stopping of the motor. The switch 107 is connected in electrical circuit with the solenoid valve 90 of the air motor 88 and, when engaged by the member 106 at the forward end of the stroke of the piston, effects a cut-off of the air pressure supplied to the air motor and an opening of the exhaust port thereof so that the piston may return to its normal position. In so returning the member 106 engages with the switches 103 and 104 thereby closing an electrical circuit to the motor 41 and effecting starting of the motor.

Lengths of tubing

It will be apparent that tubular coils of the type described require continuous lengths of tubing for the formation thereof. Depending upon the particular service requirements, such coils may be formed with one or several series of coils arranged in concentric relation. The coil assembly illustrated in Fig. 1 includes two concentric series of coils *c* and *d*, with series *d* being arranged within series *c* and in continuity therewith. Accordingly, it is contemplated that a plurality of tubing sections of commercial lengths will be welded together to provide a continuous tube of sufficient length to form the coil.

The tubing supporting means illustrated in Figs. 12 and 13 comprises a vertically adjustable base or stand 108 on which is supported a substantially U-shaped member 109 on each leg 110 of which is carried an assembly indicated generally by the numeral 111 and presently to be described. Each assembly includes a pair of vertical plates 112 shaped substantially as shown in Fig. 13 between which are supported for rotation two pairs of rollers 113 and 114 adapted to cradle a section of tubing 96 in the manner illustrated in Fig. 13. Each assembly also includes a pivoted arm 116 carrying a roller 117 adapted to be disposed in confronting relation to the rollers 113 and 114. The arm 116 is provided with an extension 118 at the free end in which is received a pivoted bolt member 119 cooperating with a wing nut 121

to draw the arm 116 and roller 117 in the direction of the rollers 113 and 114 so that the upper roller 117 engages with the tubing section 96 to hold the same firmly in position while yet permitting rotation of the tubing section. The assembly 111 additionally includes an arm 125 fixed with a ratchet wheel 120, the arm, ratchet wheel and roller rotating as a unit. A spring biased pawl member 115 cooperates with the ratchet wheel 120 to permit movement of the roller 117 only in one direction. Movement of the roller 117 in a clockwise direction, as viewed in Fig. 13 is effected through a link member 122 connected to a foot treadle 123 in a well-known manner, a tension spring 124 serving to return the associated parts to non-operating position.

As will be apparent by reference to Fig. 12, the tubing sections 96 are arranged as illustrated with their ends in abutting relation. The chamfered ends of the tubing sections are thus held securely for welding and upon completion of a welding operation on one portion of the circumferential area of the tubing sections the operator merely depresses the foot treadle 123 which effects rotation of the tubing sections a desired amount to expose another portion of the tubing for welding. Thus, it will be apparent that the tubing sections may be successively rotated to render accessible successive portions of tubing for welding.

Operation

The operation of my improved apparatus should be apparent from the foregoing, but briefly stated it is as follows. The tubing is preferably composed of a plurality of sections welded together, the ends of the sections being chamfered preparatory to welding. The prepared ends are then arranged in abutting relation, as illustrated in Fig. 12, and secured in position by tightening the wing nuts 121. The ends of the tubing sections are then welded together as with a torch in a well known manner, the operator effecting rotation of the tubing sections by manipulation of the foot treadle 123 in the manner hereinbefore described to render accessible successive portions of the tubing sections for welding. Upon completion of the welding of one joint the wing nuts 121 are released so as to permit the positioning of other tubing ends in abutting relationship. It will be apparent that the tubing must be suitably supported so as to prevent straining or buckling. For such purposes any suitable means providing rolling support for the tubing may be used, for example like those shown in Fig. 3 and indicated generally by the numeral 130. The said supports may rest on a floor surface or project from a wall surface.

Assuming that a plurality of tubing sections have been welded together so as to obtain a desired length of tubing, the said length is supported on suitable supports 130 and the end passed through the die elements 92 and 93 which in their normal position assume the open relationship illustrated in Fig. 6, with the tubing 96 engaging the groove of the leading portion of the die element 92. Depending upon the size of the tubing and the diameter of the coil to be wound, the carriage 78 and roller 71 are suitably adjusted in relation to the winding arbor 50 so as to prevent kinking of the tubing during forming. The carriage 78 is locked in position by means of the latching member 87 which is caused to engage one of the notches 86 while the roller 71 is adjusted vertically by rotation of the squared end 77 of the pinion shaft. An anchor element 131 such as illustrated in Fig. 11 is applied to the end of the tubing and is engaged with a transverse portion 66 of one of the members 63 in the manner illustrated in Fig. 3. It will of course be understood that the position of the engaged member 63 bears a definite relationship to the position of the projection 45 on the member 43 so that offsetting of the first coil convolution is at a desired point in relation to the end of the coil. The motor 41 is started by manipulating the switch 132 and the winding arbor 50 is caused to rotate in the direction of the arrow of Fig. 3. In the rota-

tion of the member 42, the projection 45 will engage with switch 40 to effect energization of the solenoid valve 90 of the air motor so as to admit compressed air into the cylinder of the motor to effect movement of the piston in a forward direction or in a position to close the die elements 92 and 93. Substantially at the beginning of such movement of the piston of the air motor the dog member 106 actuates the switches 103 and 104 to open the circuit to the motor 41 and thereby to effect stopping of the same. The piston of the air motor however continues to cause the die element 93 to move into confronting relation with the complementary die element 92 thereby bending the tubing 96 to the form illustrated in Fig. 7 so that the axes of the tubing portions on opposite sides of the angular portion are offset from each other but in parallel relation. Substantially near the end of the stroke of the piston the dog member 106 engages with the switch 107 which energizes the solenoid valve 90 to close off the air pressure supply and open an exhaust port so that the spring within the air motor may return the piston to normal position. As the dog member 106 moves with the piston rod it engages with the switches 103 and 104 so as to effect a reverse actuation thereof and again effect closing of the circuit to the motor 41 to cause the same to drive the winding arbor 50. As will be apparent when the angular portion of the tubing reaches the arbor 50 it is received in the adjoining recesses 64 of the members 63 to be formed into a convolution in a plane at a right angle to the axis of the arbor and parallel to the plane of the first convolution. When the projection 45 on the driving member 42 again engages with the switch 40 the next cycle of operations is initiated and a second offset portion is formed in the tubing in the manner hereinabove described. Thus, in the operation of the apparatus a continuous coil is formed in which the major portions of the convolutions are in parallel relation and in planes at right angles to the axis of the arbor with adjacent convolutions being connected by offset portions, all of which are in alinement. In the formation of successive convolutions in the coil, the offsetting means which include the air cylinder and the die are free to move across the length of the arbor so as to be self-aligning with the grooves in the arbor members.

Operating adjustments

As will be apparent from the drawings, the apparatus is intended to form coils with one or more tiers of convolutions arranged in concentric relation. Thus, after the first tier of convolutions, as illustrated in Fig. 1 and indicated by the letter *d*, has been wound, a plurality of coil supporting elements 133 in the form of rods formed with undulations are suitably welded to the convolutions in spaced circumferential relation, in the manner illustrated in Fig. 1. The undulations serve the same purpose as the grooves of the members 63 to guide and position the tubing during its forming operation. As will be apparent, in the forming of the second series of convolutions *c* the winding operation proceeds in a direction opposite from that first described. It will of course be understood that in view of the increased diameter of the second series of convolutions *c* adjustment of the roller 71 as well as that of the carriage 78 in relation to the winding arbor 50 is necessary in order to avoid kinking of the tubing. As will be noted in Fig. 8, the second series of convolutions *c* is arranged in staggered relation to the first series *d*. Correspondingly, if a third series of convolutions is required, supporting elements like 133 applied to the first series are suitably welded to the second series of convolutions and these elements serve as a support and guide for winding the third series of convolutions. The convolutions of the third series will be in staggered relation to the convolutions of the second series and in the same plane as the convolutions of the first series.

Upon completion of the winding of one series and

preparatory to the winding of the next succeeding series of convolutions, the position of the die elements 92 and 93 must be reversed, for as will be observed in Fig. 1, the offsetting of the convolutions of the first series *d* is in the direction of winding, to the left, while the offsetting of the convolutions of the second series *c* is correspondingly in the direction of winding, but in this instance to the right. In order to effect a change in the direction of offsetting of the tubing, it is merely required to release the die elements 92 and 93 which may be effected by removing the pin 98 and bolt 105, slide the die elements 92 and 93 out from between the confining plates 89 and 91, turn them upside down and replace them between the said plates, securing them with the pin 98 and bolt 105. Thus, it will be apparent that the direction of the offset is opposite from that first described.

Upon completion of the winding of the coil the crank or wheel 34 is rotated so as to turn the lead screw 32 in a counterclockwise direction to effect movement of the bearing 28 to the right as viewed in Fig. 2 thus permitting removal of the forming arbor and the coil. This of course is effected by drawing the arbor 50 and the coil to the right, as viewed in Fig. 2, to effect disengagement of the disc member from the pins 44 on the driving member 42. Thereafter, upon the application of tension in opposite directions to the chamfered discs the arbor elements 63 are caused to move inwardly radially to the position illustrated in Fig. 10, thereby effecting a reduction in the effective diameter of the winding arbor and providing sufficient clearance so that the arbor may be easily removed from the inside of the coil.

While Fig. 10 shows the arbor with the shaft removed therefrom, it will be understood that removal of the shaft is not required in all cases, but is dependent upon the diameter of the tubings and the diameter of the coil being formed, since it is conceivable that a partial collapse of the arbor may provide sufficient clearance for easily removing the arbor from the formed coil.

It will be apparent that a variety of sizes of winding arbors may be used with the driving apparatus, it being only necessary to withdraw the bearing journal 28 to permit removal of the arbor 50 in the manner described and when the pins 44 are engaged with the plate 56 of the new arbor, the bearing 28 is moved to the left, as viewed in Fig. 2, to receive the end of the arbor shaft 51. The end vertical face of the bearing 28 serves to retain the members 63 in expanded condition, as illustrated in Figs. 2 and 9. Correspondingly the same apparatus may be used with die elements of various sizes so that a variety of sizes of tubing may be used for forming coils of various diameters.

I claim:

1. An apparatus for forming tubing into coils comprising a supporting structure, a winding arbor rotatably mounted in said structure and provided with means comprising a plurality of spaced apart bars for supporting convolutions of tubing thereon, an anchor element having a rigid ring portion embracing an end portion of the tubing and having a recessed portion providing a hook-shaped jaw which fits over and frictionally clamps a portion of a tubing supporting bar for releasably attaching one end of the tubing to the arbor, and means for rotating said arbor; the said spaced apart bars for supporting said convolutions being movable inwardly toward the longitudinal axis of the arbor and out of contact with the formed tubular coil to facilitate removal of said coil.

2. In apparatus for automatically forming tubing into concentrically arranged coils of different diameters, the convolutions of which are provided with offsets defining angular portions disposed in horizontal arrangement with the ends of adjacent offset portions aligned horizontally with each other in planes extending parallel to the longitudinal axis of said arbor, the combination of a winding arbor having means for supporting convolutions of tub-

ing thereon, electrically energized power means for rotating said arbor to wind the tubing thereon, means comprising a carriage disposed in advance of said arbor and movable lengthwise thereof to support an unwound length of tubing in alignment with successively formed convolutions, means on said carriage comprising a fixed die element, a movable die element and means for operating the movable die element to form offsets in the said unwound length of tubing at predetermined locations, electrical means controlled by the operation of said arbor for activating the die operating means, switch means actuated by movement of said die operating means in one direction to de-energize the arbor rotating means during said offsetting operation, switch means actuated by reverse movement of said die operating means to re-energize said arbor rotating means, and a second carriage arranged for movement in a direction at right angles to the axis of rotation of said arbor and providing a support for the first mentioned carriage, whereby the position of said offsetting dies relative to the arbor may be varied to increase or decrease the linear distance measured circumferentially of the coil between said offsets.

3. In apparatus for automatically forming tubing into coils of different diameters, the convolutions of which are provided with offsets defining angular portions disposed in horizontal arrangement with the ends of adjacent offsets aligned horizontally with each other in planes extending parallel to the longitudinal axis of the arbor, the combination of a winding arbor having means for supporting convolutions of tubing thereon, electrically energized means for rotating said arbor to wind the tubing thereon, means comprising a carriage disposed in advance of said arbor and movable lengthwise thereof to support an unwound length of tubing in alignment with successively formed convolutions, means on said carriage comprising a fixed die element, a movable die element and means for operating the movable die element to form offsets in the said unwound length of tubing at predetermined locations, electrical means controlled by the operation of said arbor for actuating the die operating means, switch means actuated by movement of said die operating means in one direction to de-energize the arbor rotating means during said offsetting operation, switch means actuated by reverse movement of said die operating means to re-energize said arbor rotating means, a second carriage arranged for movement in a direction at right angles to the axis of rotation of said arbor and providing a support for the first mentioned carriage, whereby the position of said offsetting dies relative to the arbor may be varied to increase or decrease the linear distance measured circumferentially of the coil between said offsets.

4. In apparatus for automatically forming tubing into coils of different diameters, the convolutions of which are provided with offsets defining angular portions disposed in horizontal arrangement with the ends of adjacent offset portions aligned horizontally with each other in planes extending parallel to the longitudinal axis of the arbor, the combination of a winding arbor having means for supporting convolutions of tubing thereon, electrically energized means for rotating said arbor to wind the tubing thereon, means comprising a carriage disposed in advance of said arbor and movable lengthwise thereof to support an unwound length of tubing in alignment with successively formed convolutions, means on said carriage comprising a fixed die element, a movable die element and means for operating the movable die element to form offsets in the said unwound length of tubing at predetermined locations, electrical means controlled by the operation of said arbor for actuating the die operating means, switch means actuated by movement of said die operating means in one direction to de-energize the arbor rotating means during said offsetting operation, switch means actuated by reverse movement of said die operating means to re-energize said arbor rotating means, a second carriage arranged for movement in a direction at right angles to the axis of rotation of said arbor and providing a support for the first mentioned carriage, whereby the position of said offsetting dies relative to the arbor may be varied to increase or decrease the linear distance measured circumferentially of the coil between said offsets, and means for locking the second carriage in its various adjusted positions.
